UNITED STATES PATENT OFFICE.

VAN SCHAICK SHARP, OF WEEDSPORT, NEW YORK, ASSIGNOR OF TWO-THIRDS TO WALLACE W. HOLCOMB AND HOMER E. RHEUBOTTOM, OF SAME PLACE.

MACHINE FOR SEAMING SHEET METAL.

SPECIFICATION forming part of Letters Patent No. 324,736, dated August 18, 1885.

Application filed June 25, 1885. (No model.)

To all whom it may concern:

Be it known that I, VAN SCHAICK SHARP, a citizen of the United States, residing at Weedsport, in the county of Cayuga and State 5 of New York, have invented new and useful Improvements in Machines for Forming Cross-Lock Seams in Metal Sheets, of which the following is a specification.

The object of this invention is to provide a 10 simple and accurately-working machine for securely locking the cross-seams of connected sheets of tin or other similar metal intended for roofing or other purposes.

The machine illustrated in the annexed 15 drawings embraces a suitable stand on which is mounted a bed-plate with vertically-slotted heads arranged at each end and provided with guides or gages for aligning the seam to be locked, the closing of the seam being effected 20 by the pressure of a roller that moves forward and back over the bed-plate and seam and beneath a vertically-adjustable bar supported in said heads, and by which the pressure of said roller is controlled. The connected sheets in 25 succession, with securely-locked joints or seams, are wound in a continuous strip on a reel provided for the purpose, and from which they are removed when the strip attains sufficient length.

30 My invention consists in certain novel features of construction, as hereinafter set forth.

Referring to the annexed drawings, Figure 1 is a perspective view of a machine embodying my invention for forming cross-lock seams 35 in metallic strips or sheets for roofing and other purposes. Fig. 2 is an end view, partly in transverse section; and Figs. 3 and 4 are detail views.

The reference-numeral 1 designates a suitable stand or table having legs 2 or other convenient supports. On this stand or table 1 is mounted a cast-metal bed-plate, 3, having at each end an upright malleable iron head, 4, said upright heads being vertically slotted and secured firmly to the top of the table by screw-bolts or otherwise. In the upper part of these vertically-slotted upright heads 4 is adjustably supported a horizontal longitudinally-slotted pressure-bar, 5, by means of adjusting-screws 6, passed through the sides of the slot-

ted heads, as shown in Fig. 2, and by which said pressure-bar can be held at any height, as required.

A roller, 7, is journaled in the bifurcated or slotted end of a reciprocating arm, 8, in such a manner as to be capable of moving along and over the bed-plate 3 from end to end, and with its upper portion rotating within the slotted malleable iron bar 5, which thus serves as a guide for the roller. On each side of the roller 60 5 is a smaller roller or roller-surface, 9, that fits beneath the adjacent side of the slotted bar 5, to give greater ease of motion to the larger or main pressure-roller 7, which can thus be made to exert a greater or less degree of pressure by simply varying the vertical adjustment 65 of the slotted bar. After this slotted bar has been adjusted to the required height it can be firmly held from any tendency to vertical displacement due to the upward pressure of the 70 roller by means of a binding-screw, 6^a, at each end, these screws being turned down vertically upon the ends of the slotted bar 5, so as to hold it securely in place.

The bed-plate 3 is provided on one side with 75 gages 10, by which the seamed portions of the metallic sheets or strips to be united are aligned and held in place while the seam is being securely locked by the pressure of the roller.

In order to avoid any difficulty in starting the roller 7, and for the purpose of overcoming the obstructions that would be encountered by its abrupt pressure against the edges of the metal strips or sheets at the ends of the 85 seam to be acted on, a yielding guide, 11, is arranged near one end of the bed-plate in such position as to partly cover the abrupt end of the seam, and so allow the roller to pass smoothly onto the sheet of tin or other material. Beneath one end of this guide is a small expansion-spring, 12, that holds the guide to close contact with the edge of the seam inserted beneath its opposite end. The pressure of the roller 7 in its return movement 90 compresses this spring, thereby depressing that end of the guide and raising the opposite end, so that another seam can be inserted thereunder. It will be seen that this guide is thus so arranged as to offer no obstruction 95 100

to the free passage of the roller in either direction.

The roller 7 is actuated through the reciprocating arm or rod 8, which is hinged at its outer end to the upper extremity of an oscillating rod or lever, 13, that is pivoted at or below its center to a bracket, 14, projecting from one end of the machine-frame, and stayed by braces 15, secured to the upper part of the frame. The lower end of the rod or lever 13 is hinged or jointed to one end of a lever, 16, the opposite end of which is jointed to or hinged into one end of a rod or lever, 17, which is pivotally connected at its other end 15 to a transverse rod, 18, that is secured within one end of the machine-frame, and braced by stay-rods 19, that extend diagonally to the opposite end of the frame. The rod or lever 17 is connected by a depending link or short 20 connecting-bar, 20, to a foot-treadle, 21, the inner end of which may be pivoted between the lower ends of the vertical brace-bars 22, that are arranged at one end of the machine-frame. To the treadle 21 is also attached a 25 spiral spring, 23, the upper end of which is connected to one end of the stand or table.

A reel, 24, is journaled in bearings 25 at one side of the machine, preferably above the level of the bed-plate, and is provided with a 30 crank-handle, 26, a ratchet, 27, and a pawl, 28, for the purpose of forming the connected sheets of tin or other metal into a convenient roll for transportation.

In operating the machine two sheets of tin 35 or other metal to be connected are arranged with their edges properly turned and hooked together, the turned edges being then placed against the gages 10 on the bed-plate and subjected to the pressure of the roller 7, actuated 40 by the treadle 21 and its connections. By pressure on the treadle 21 the rods or levers 8, 13, 16, and 17 will be actuated through the link 20 in such a manner as to cause the roller 7 to be passed forward over the adjacent engaged edges of the metal sheets, and by releasing the treadle it will be drawn up by the spring 23, thereby reversing the movement of said lever-rods, so as to draw the roller 7 backward over the seam, which is thus securely 50 locked. After one lock-seam is thus formed another sheet of metal with turned-over edge is engaged with the turned-over edge at the free end of one of the sheets just acted on, and the operation repeated, as above described, the successive sheets of connected metal being wound on the reel 24 as the operation progresses. It will be seen that both movements of the pressure-roller 7, forward and back, are produced by a single downward 55 pressure on the treadle 21, followed by its release when the roller has reached its forward limit.

It is obvious that by means of the adjusting-screws 6 and 6^a the slotted bar 5 can be securely held after it has been raised or lowered at any time during the progress of the work, so as to regulate the pressure of the roller 7,

or for the purpose of accommodating seams or sheets of varying thickness.

After successive sheets of metal have been 70 connected, locked together with cross-seams, and rolled onto the reel until the desired length is obtained, the long sheet thus formed and rolled can be readily slipped off the reel by removing the latter from its bearings. 75

This manner of cross-seaming the sheets of tin or other metal allows a great saving in solder, as the seams may be safely left without soldering when the connected sheets are used for roofing and other purposes; or, if the 80 employment of some solder is preferred, a much less quantity is required than is necessary with hand-locked cross-seams. By this machine, also, the work of forming cross-lock seams in connected sheets of tin or similar metal can be 85 accomplished with great rapidity and accuracy as compared with hand-work or the use of ordinary appliances.

Having thus described my invention, what I claim is—

1. In a machine for connecting metal sheets with lock-joints, the combination of a bed-plate, vertically-slotted heads, a longitudinally-slotted bar arranged above and parallel with the bed-plate, and vertically adjustable 95 at each end within said slotted heads, and a roller arranged to travel along the bed-plate within the slot and under the pressure of said bar and over the seam or joint to be locked, substantially as described.

2. The combination of a bed-plate having gages for aligning the work, vertically-slotted heads arranged at the opposite ends of said bed-plate, a longitudinally-slotted horizontal bar vertically adjustable in said slotted heads, 105 and a pressure-roller arranged to be moved forward and back along the bed-plate and beneath and within the horizontal slotted bar, whereby a lock joint or seam in two connected sheets of metal is formed by the pressure of said roller, substantially as described.

3. The combination of a bed-plate having a yielding guide, a roller arranged to move forward and back over said guide and bed-plate and over the work lying thereon, and a vertically adjustable bar to vary the pressure of the roller and enable it to accommodate itself to varying thicknesses of material acted upon, substantially as described.

4. The combination of a bed-plate, a pressure-roller arranged to move forward and back over said bed-plate and over the work supported thereon, said pressure-roller being provided with side rollers, 9, of smaller diameter, and a vertically-adjustable slotted bar arranged parallel with and above the bed-plate, and arranged to bear on the small rollers on each side of the pressure-roller to regulate the pressure of the latter, substantially as described.

5. The combination of the bed-plate 3, having gages 10 and yielding guide 11, the slotted heads 4, adjustable pressure-bar 5, reciprocating lever 8, pressure-roller 7, journaled

in one end of said reciprocating lever, and provided with side rollers, 9, and means for actuating said lever, substantially as described.

6. The combination of the table 1, bed-plate 5 3, vertically-adjustable slotted bar 5, roller 7, moving within the slot of the pressure-bar, and having side rollers, 9, the reciprocating lever 8, rods or levers 13 16 17, treadle 21, link 20, and spring 23, substantially as described.

In testimony whereof I affix my signature in presence of two witnesses.

VAN SCHAICK SHARP.
